UNITED STATES PATENT OFFICE

112,402

DESIGN FOR TROUSERS

Herbert M. Birch, Washington, D. C.

Application April 15, 1937, Serial No. 68,789

Term of patent 7 years

To all whom it may concern:

Be it known that I, Herbert M. Birch, a citizen of the United States, residing at Washington, in the District of Columbia, have invented a new, original, and ornamental Design for Trousers, of which the following is a specification, reference being had to the accompanying drawing, forming part thereof.

The figure is a front view of a pair of trousers showing my design.

The characteristic feature of my invention resides in a design for a pair of trousers comprising a yoke with a sailor fly or button opening in the front and relatively open net leg portions se-

cured to the yoke with elongated cloth strips made of the yoke material extending from the bottom of each net leg appliquéd to the yoke on each side and below the button opening in substantial alignment with the buttons on the yoke at each side of the opening.

The rear of the trousers is identical with the front except for the above described button opening.

I claim:—

The ornamental design for trousers, as shown and described.

HERBERT M. BIRCH.
